(57) **CLAIM**

The ornamental design for an anatomical sensor, as shown and described.

DESCRIPTION

FIG. 1 is a perspective view of the anatomical sensor;

FIG. 2 is a top view of the anatomical sensor;

FIG. 3 is a bottom view of the anatomical sensor;

FIG. 4 is a left side elevational view of the anatomical sensor;

FIG. 5 is a right side elevational view of the anatomical sensor;

FIG. 6 is a top elevational view of the anatomical sensor; and,

FIG. 7 is a bottom elevational view of the anatomical sensor.
